UNITED STATES PATENT OFFICE.

WILLIAM T. SMITH, OF BOLTON, ENGLAND.

SPINNING COTTON AND APPARATUS THEREFOR.

1,128,193.

Specification of Letters Patent.

Patented Feb. 9, 1915.

Application filed March 13, 1911. Serial No. 614,164.

To all whom it may concern:

Be it known that I, WILLIAM THOMAS SMITH, a British subject, residing at Bolton, county of Lancaster, England, have invented 5 certain new and useful Improvements in Spinning Cotton and Apparatus Therefor, of which the following is a specification.

This invention is designed to provide for the steaming or humidifying of cotton rove 10 during spinning without raising the humidity of the spinning room to any very appreciable extent.

It consists in passing cotton rove through steam or aqueous vapor during the spinning 15 process and in arranging on the spinning machine a trough to contain hot water, or a perforated steam pipe through the vapor from which the rove ends are passed, the water either being heated in or caused to 20 circulate through the trough.

The invention will be fully described with reference to the accompanying drawings forming part of the specification.

Figure 1 is a transverse section of spinning frame head. Fig. 2 is a longitudinal section through the trough A.

Between the bobbin creel (not shown) of the spinning frame and the drawing rollers G a trough A is fitted through which the 30 rove R is drawn. The trough A is partially filled with hot water which circulates therein and above the water level a perforated guard D is placed to prevent the rove R from coming into contact with or entering 35 the water. The trough A is covered with a well fitting lid C, holes, slots or spaces f f' being provided at both sides of the trough for the entrance and exit of the rove R as it passes from the creel to the rollers G.

40 The trough A is constructed with inner and outer casings a a' between which is a packing B of a material which is a non-conductor of heat. The lid C is similarly made of inner and outer casings c c' between 45 which a non-heat-conducting packing material B is placed. The lid or cover C may be hinged to the trough A and is preferably held in position by clips or bolts; the joints between the lid C and the trough are preferably provided with recesses e e' which are packed with a soft yielding material to 50 make a tight joint. The trough A may be made of metal or wood.

The perforated guard D in the interior of 55 the trough A is held in position by supports d d' which rest upon the sides of the inside

casing. The perforated guard D may be of one piece the length of the trough or it may consist of a number of short lengths to facilitate its removal from the trough for 60 cleaning purposes.

The rove R enters the trough A through one of the holes f' at one side and leaves it by the corresponding hole f at the other side and then passes to the drawing rollers G. 65 These holes f f' are preferably of the shape shown and consist of eyelets passing through the non-conducting material B.

The hot water enters the trough A through the pipe H which extends nearly 70 the whole length of the trough A then passes back through the trough over the baffle plate h to the outlet pipe h'. To prevent the rove taking up too much water during stoppage of the machine a second outlet pipe h² is situated behind the baffle plate h. This pipe h² is provided with a valve h³ which is connected with a valve h⁴ in the inlet pipe H. Both these valves are connected up with strap fork of 75 the machine so that on the strap being moved onto the loose pulley the valve h⁴ is closed and the valve h³ opened thus cutting off the supply of water and allowing the water in the trough to drain off.

Instead of circulating hot water, the water 80 may remain in the trough and be heated by steam introduced through the pipe H in the trough. Instead of hot water the pipe H may be perforated to distribute steam 90 into the trough A.

The hot water supply can be from the heating installation of the room or other boiler or hot water supply or a Bunsen burner may be used for the same purpose, or 95 it may be heated by a steam pipe or the like.

The trough may be supported on sliding or adjustable stands to regulate the height and allow for the necessary incline to drain 100 the trough.

By this invention the cotton rove R as it passes over the water is steamed or moistened by the vapor but is not passed through or saturated with the water as is the case in 105 wet doubling or the wet spinning of flax.

What I claim as my invention and desire to protect by Letters Patent is:—

1. A humidifier for cotton rove comprising a closed trough adapted to contain hot 110 water, the opposite sides of the trough being provided with alining guide openings for

the rove, a water supply pipe entering one end of said trough and terminating adjacent the opposite end thereof, a baffle plate disposed adjacent the first-named end of the 5 trough, an outlet pipe leading from said trough adjacent said first-named end, and a perforated guard plate supported within said trough above the level of the water therein and below said openings to permit 10 the vapor rising from the water to have direct access to said rove, but preventing the latter from coming into contact with the water.

2. A humidifier for cotton rove comprising 15 a closed trough adapted to contain hot water, the opposite sides of the trough being provided with alining guide openings for the rove, a valved water supply pipe entering one end of said trough and terminating 20 adjacent the opposite end thereof, a baffle

plate disposed adjacent the first-named end of the trough, a valved outlet pipe leading from said trough adjacent said first-named end, a connection between said valves for simultaneously opening either valve and 25 closing the other, and a perforated guard plate supported within said trough above the level of the water therein and below said openings, to permit the vapor rising from the water to have direct access to said 30 rove, but preventing the latter from coming into contact with the water.

In testimony whereof I have hereunto set my hand in presence of two subscribing witnesses.

WILLIAM T. SMITH.
